REFRIGERATION

Albert R. Thomas, Evansville, Ind., assignor to
 Servel, Inc., New York, N. Y., a corporation of
 Delaware

Application November 22, 1939, Serial No. 305,578

1 Claim. (Cl. 62—125)

My invention relates to refrigeration, and has for its object to provide an improvement in a heat transfer system in which cooling is produced at a place above a source of refrigeration.

The above and other objects and advantages of the invention will become apparent from the following description and accompanying drawing forming a part of this specification, and of which the single figure more or less diagrammatically illustrates an embodiment of the invention.

The heat transfer system is shown in connection with a cooling element or evaporator 10 of an absorption refrigeration system employing an inert gas and like that described in my application Serial No. 107,852 filed October 27, 1936, now Patent No. 2,207,838, granted July 16, 1940. The cooling element 10 constitutes a source of refrigeration and includes an outer shell 11 which is embedded in insulation 12. Liquid refrigerant, such as ammonia, enters the upper part of cooling element 10 through a conduit 14. An inert gas, such as hydrogen, enters the upper part of the cooling element from the upper end of a cylinder 15 disposed within shell 11. Liquid refrigerant evaporates and diffuses into inert gas within cooling element 10 to produce a refrigerating effect. This refrigerating effect is utilized to cool and liquefy a volatile fluid flowing through a coil 16 which is arranged about the cylinder 15 and over which the liquid refrigerant flows from an annular vessel 17. In order to simplify the drawings, only the cooling element 10 of the refrigeration system has been shown, an illustration of the other parts of the system not being necessary for an understanding of this invention. The disclosure in my aforementioned application may be considered as being incorporated in this application, and, if desired, reference may be made thereto for a detailed description of the refrigeration system.

The coil 16 constitutes the condenser of a heat transfer system which is formed and arranged so that cooling may be effected at a higher elevation than the cooling element 10. The heat transfer system includes an evaporator 18 which is of a flooded type and located at a higher elevation than condenser 16. The evaporator 18 is disposed in the upper part of a thermally insulated space 19 of a refrigerator cabinet or cooler 20. The cooler or refrigerator cabinet 20 may be of the walk-in type having a door 21 to permit a person to walk into the space 18.

The evaporator 18 includes a receiver 22 having a looped coil 23 connected thereto. A plu-

rality of heat transfer fins 24 are fixed to coil 23 to increase the heat transfer surface of the evaporator. The upper part of receiver 22 is connected by a conduit 25 to the upper part of condenser 16. The lower part of condenser 16 is connected to a receiver 9 which in turn is connected to a vertically extending standpipe 8. The receiver 9 and standpipe 8 are embedded in insulation 26 retained in a shell 27.

The lower end of standpipe 8 is connected by a horizontally extending conduit 28 to the lower end of a looped coil 29. The conduit 28 extends through an insulated wall of refrigerator cabinet 20 and is inclined upwardly from the lower end of standpipe 8. The looped coil 29 is located near the floor of thermally insulated space 19 and provided with a plurality of heat transfer fins 30 to increase the heat transfer surface of this part of the heat transfer system. The upper end of coil 29 is connected by a vertically extending riser conduit 31 to the upper part of receiver 22.

A fan 32 is arranged adjacent the looped coil 29 to cause flow of air over the latter. The fan 32 is driven by an electric motor 33 which is connected by conductors 34 and 35 to a suitable source of electric energy. In the conductor 34 is connected a snap-action switch 48 having toggle arms 36 and 37 pivoted at 38 to a suitable support 39. The arms 36 and 37 at points intermediate their ends are connected by a spring 40 which is operative to cause the arms 36 and 37 to move with a snap action.

To the toggle arm 36 is pivotally connected the lower end of a link member 41, the upper end of which is connected to an expandable and contractible bellows 42. The upper end of bellows 42 is fixed to a support 43. The bellows 42 is connected by a capillary tube 44 to a thermal bulb 45 located within space 19 so that it is responsive to the average temperature of air in the space. The bellows 42, tube 44 and bulb 45 constitute an expandible fluid thermostat which is filled with a suitable volatile fluid.

In the position shown in the drawing it will be observed that upward movement of toggle arm 37 is limited by a stop 46. When toggle arms 36 and 37 are moved downward from the position shown, the arm 37 engages a contact 47, thereby limiting downward movement of toggle arm 37. When toggle arm 37 engages the contact 47 the circuit for motor 33 is completed and operation of fan 32 will be started.

The heat transfer system including evaporator 18, condenser 16, looped coil 23 and the inter-

connecting conduits form a closed fluid circuit which is partly filled with a suitable volatile liquid, such as methyl chloride, for example. All of the parts of the heat transfer system are in unrestricted communication and the closed fluid circuit may be referred to as being of a uniform pressure type.

During operation of the heat transfer system, liquid evaporates in evaporator 18 and takes up heat thereby producing cold. The vapor formed in evaporator 18 flows through conduit 25 into condenser 16 in which the vapor is cooled and condensed by cooling element 10. The condensate formed in condenser 16 flows therefrom through receiver 9, standpipe 8 and conduit 28 into looped coil 29. Liquid is raised through riser conduit 31 to the evaporator 18 at a higher level by vapor liquid lift action. This results from heating of liquid in the looped coil 29 and lower part of conduit 31 by air in thermally insulated space 19. Due to such heating vapor bubbles are formed in the looped coil 29 and lower part of conduit 31. The internal diameters of looped coil 29 and conduit 31 are sufficiently small so that these vapor bubbles cannot freely pass liquid whereby slugs of liquid are raised by vapor liquid lift action. The column of liquid formed in standpipe 8 balances the column of liquid slugs and vapor raised in conduit 31 to provide the necessary reaction head for raising liquid to the evaporator 18 at the higher level.

In order to maintain a uniform temperature in thermally insulated space 19, the small looped coil 29 is provided in the heat transfer system near the floor of the cooler 20. The looped coil 29 is relatively small compared to the evaporator 18 which is arranged in the upper part of thermally insulated space 19 and at which region heat is abstracted to maintain the space 19 at a desired low temperature.

When the average temperature in space 19 tends to rise above a predetermined value, the volume of the volatile fluid in the expansible fluid thermostat increases and the bellows 42 expands sufficiently to move toggle arms 36 and 37 downwardly from the position shown in the drawing and cause toggle arm 37 to engage the contact 41. With toggle arm 37 engaging contact 41 the circuit for motor 33 is completed and fan 32 will start operating. The fan 32 causes air to flow over the surfaces of looped coil 29 and fins 30 whereby heat is transferred to liquid in looped coil 29 and the lower part of conduit 31 more rapidly than during the periods when fan 32 is not operating and natural circulation of air takes place in space 19. Since heat is transferred to liquid in looped coil 29 and the

lower part of conduit 31 at a more rapid rate when air is caused to flow over these parts by fan 32, vapor bubbles are formed more rapidly and liquid will be raised through conduit 31 at a faster rate by vapor liquid lift action.

When the average temperature in space 19 tends to fall below the predetermined value, the volatile fluid in the expansible fluid thermostat becomes reduced in volume and bellows 42 contracts sufficiently to move toggle arms 36 and 37 to the upper position shown in the drawing. With toggle arm 37 no longer engaging contact 41, the circuit for motor 33 is opened and the fan 32 stops running. During the periods when fan 32 is not operating, circulation of air takes place naturally in thermally insulated space 19, that is, air cooled by evaporator 18 flows downward to replace warmer air rising in space 19.

The receiver 9 is of sufficient volume to provide a place of storage for liquid when evaporator 18 is only partly filled with liquid.

In view of the foregoing, it will be clear that the provision of the looped coil 29 in the heat transfer system and the thermostatically controlled fan 32 is particularly advantageous in that a more uniform temperature may be maintained in thermally insulated space 19. In addition to maintaining a uniform temperature in space 19, desirable forced circulation of air in the space is obtained during the periods when fan 32 is operating.

While a single embodiment of the invention has been shown and described, such variations and modifications are contemplated which fall within the true spirit and scope of the invention, as pointed out in the following claim.

What is claimed is:

In a refrigerator having a storage compartment, a cooling element, a heat transfer system including an evaporator in the upper part of said compartment, a condenser at a level below that of said evaporator and arranged to be cooled by said cooling element and connected to receive vapor from said evaporator, a second evaporator in the lower part of said compartment connected to receive liquid from said condenser, a conduit for conducting liquid from said second evaporator upward to said first evaporator under the lifting action of vapor formed in said second evaporator, a blower located so as to direct a stream of air in said compartment onto said second evaporator when the blower is in operation, and a thermostat for starting and stopping said blower responsive to change in temperature of air in said compartment.

ALBERT R. THOMAS.
